CHARLES KALLMANN, OF NEWBURG, NEW YORK.

Letters Patent No. 88,718, dated April 6, 1869.

COMBINED CLOCK AND FLY-TRAP.

The Schedule referred to in these Letters Patent and making part of the same

To all whom it may concern:

Be it known that I, CHARLES KALLMANN, of Newburg, in the county of Orange, and State of New York, have invented a new Combination of a Clock and a Fly-Trap; and I do hereby declare that the following is a full, clear, and exact description thereof, reference being had to the annexed drawings, and to the letters of reference marked thereon.

Figure 1 represents a front view of the clock.

Figure 2 is a vertical section of the case enclosing the clock and the fly-trap.

Figure 3 shows a plan of a horizontal section of the same.

The nature of my invention consists in combining two useful instruments into one, the clock and the fly-trap, driving both by one moving-power, and by the same gearing.

The power required to revolve a small cylinder, D, which is covered with cloth, which is saturated with a solution of sugar or molasses in water, to invite flies and mosquitoes to sit down on the drum, is so very small that, if it is attached to a clock, its effect would hardly be felt by the spring of the clock, or a new spring, the least stronger, would keep the cylinder also in motion, without retarding the motion of the clock.

The clock-work is easily so arranged to allow one shaft to be extended, or another shaft to be attached, to which the shaft of the drum of the fly-trap is to be coupled.

The bearings which carry the cylinder are carefully put in line, and fastened to the sides of the box, which encloses the whole apparatus.

In this way, the fly-trap will be in operation as long as the clock is running, and can easily be attached to a clock running one day or eight days, or more, and requires, for this reason, less attention than any other fly-trap which has to be wound up every few hours.

The case, enclosing the whole apparatus, is so constructed that the top, O, and one side, Q, and a part of the back, O', can be removed in one piece, exposing, after removal, the cylinder D of the fly-trap, partially for the admittance of flies, &c.

Another separate case, C, fastened to the front-piece

A, encloses the clock-work, and protects it against injury from outside, when the fly-trap is in operation.

A small shaft, E, of the clock, or one expressly attached for this purpose, extends through the back of this case, and is coupled to the drum-shaft, which rests at the other end in the bearing F, and receives its motion from the spring which is driving the clock.

G is the dark chamber, into which the flies are brought, when sitting down on the drum D.

About in a horizontal line with the drum-shaft, a small rod, P, is stretched across the chamber, close to the face of the drum, so that flies cannot pass.

The rod will force them off, and the flies will escape out the dark room through a hole, I, cut in the top-board H, of the room G, and through the small holes n n n, through which light is falling from above.

Over the hole I is placed a box, K, the bottom, M, of which contains a number of small holes, n n, large enough to allow flies or mosquitoes to pass through into the box K, which is covered by a pane of glass, L, to admit light, through the holes n n and I, into the room G, and to close the box K, in which the flies, &c., are then captured.

The box K can be removed and emptied as often as convenient.

In times when the fly-trap is not used, the part of the outside case which covers the apparatus is easily put back in its place, and firmly secured by a hook and eye-bolt, S s, to the front-piece A.

The whole apparatus has then only the appearance of a clock, but it keeps the drum of the trap constantly revolving, as regular as the clock itself is going, and, by practical trials, it is confirmed that it has no influence on the regular motion of the clock.

What I claim as my invention, and desire to secure by Letters Patent, is—

The combination of the clock and the fly-trap, driven by the same moving-power, spring or weight, and by the same gearing, substantially, and the whole arranged as specified.

C. KALLMANN.
